CLAIM

The ornamental design for a spray actuator cap, as shown and described.

DESCRIPTION

FIG. 1 is a perspective view from the right side showing my new design;

FIG. 2 is a right side elevational view;

FIG. 3 is a front elevational view;

FIG. 4 is a rear elevational view;

FIG. 5 is a left side elevational view;

FIG. 6 is a top plan view; and,

FIG. 7 is a bottom plan view.

The broken line showing of a bottle is for illustrative purposes only and forms no part of the claimed design.
